DESIGN FOR A SHAPER TABLE

Herbert E. Tautz, Milwaukee, Wis., assignor to The Delta Manufacturing Company, Milwaukee, Wis., a corporation of Wisconsin

Application June 19, 1937, Serial No. 69,913

Term of patent 7 years

To all whom it may concern:

Be it known that I, Herbert E. Tautz, a citizen of the United States, residing at Milwaukee, in the county of Milwaukee and State of Wisconsin, have invented a new, original, and ornamental Design for Shaper Tables, of which the following is a specification, reference being had to the accompanying drawing, forming part thereof,

In the drawing,

Fig. 1 is a perspective view of a shaper table showing my new design, and

Fig. 2 is an end elevation thereof.

I claim:

The ornamental design for a shaper table, as shown,

HERBERT E. TAUTZ.
